UNITED STATES PATENT OFFICE.

OLE L. LARSON, OF MINNEAPOLIS, MINNESOTA.

CORRUGATED ROTARY SIEVE.

1,149,375.

Specification of Letters Patent. Patented Aug. 10, 1915.

Application filed February 20, 1914. Serial No. 819,959.

To all whom it may concern:

Be it known that I, OLE L. LARSON, a citizen of the United States, residing at Minneapolis, in the county of Hennepin and 5 State of Minnesota, have invented certain new and useful Improvements in Corrugated Rotary Sieves; and I do hereby declare the following to be a full, clear, and exact description of the invention, such as 10 will enable others skilled in the art to which it appertains to make and use the same.

My invention has for its object to provide an improved rotary sieve especially adapted for use in the separation of wild, 15 as well as tame oats from wheat and similar grain.

Generally stated, the invention consists of the novel construction and arrangement of parts hereinafter described and defined 20 in the claims.

As is well known, oats are relatively long and slender, as compared with wheat, so that when presented endwise to a sieve, they will go through perforations or mesh that 25 are so small that good wheat will not pass therethrough. The great difficulty has been to present the oats endwise to the mesh of the sieve. I have discovered that this may be efficiently accomplished by the use of a 30 corrugated tubular rotary metallic sieve.

The tubular rotary sieve is made of woven wire netting or screening material of the proper mesh and of sufficient rigidity to maintain its corrugated form. The meshes 35 or perforations of the sieve must be in the walls of the corrugations, as well as in the inner and outer portions thereof, for a very important reason which will be hereinafter more fully explained.

40 In the accompanying drawings which illustrate the invention, like characters indicate like parts throughout the several views.

Referring to the drawings: Figure 1 is a 45 vertical section taken centrally and longitudinally through a rotary corrugated sieve designed in accordance with my invention; Fig. 2 is a section taken on the line $x^2 x^2$ on Fig. 1; and Fig. 3 is a section 50 taken on the line $x^3 x^3$ on Fig. 1.

The numeral 1 indicates the body of the corrugated tubular sieve, the same, as shown, being made from stiff wire netting bent into approximately cylindrical form with its 55 edges united at 1^a, by means of solder, or otherwise. The surface of this sieve 1 is

formed with circumferentially spaced, longitudinally extended corrugations which are so closely positioned that all of the surface of the said sieve is corrugated. This rotary 60 sieve should be set at an incline so that the succotash, or grain being separated thereby, will be continuously fed from the upper toward its lower end. The upper end of the corrugated sieve 1 is, as shown, telescoped 65 onto a wooden ring 2 and the inner end portions of its corrugations are attached to the said ring at 3, by means of nails, staples, or other suitable devices. It is not necessary to fasten the outer portions of the corrugations, nor to form the supports therefor to fit the corrugations thereof, because the said corrugations are self-sustaining, that is, they keep the form into which they are pressed. The ring 2 is, as shown, secured to a larger ring 3 and a metal hoop 4 70 is secured on the ring 3 and overlaps the adjacent corrugated end of the sieve. A diametrically extended bearing 5 is secured to the ring 2 and, as shown, is provided with 75 a hub 6 located at the axis of the sieve. A metallic hoop 7 surrounds the lower end of the corrugated sieve 1 and is secured to the outer portions of the corrugations of said sieve at 8, by means of solder, or otherwise. 80 A diametrically extended bar 9 is secured to the loop 7, and is provided with a hub 10 located at the axis of the rotary sieve. A shaft 11 is extended axially through the sieve and through the hubs 6 and 10 of the 85 bearings 5 and 9, and is shown as secured to the said hubs by set screws 12. The upper and lower ends of the shaft 11 are journaled in bearings 13 and 14, respectively. 90 Rotary motion may be imparted to the inclined sieve, by any suitable means, such, for example, as by a crank, not shown, for rotating it by hand, or by a gear, pulley, or sprocket, not shown, for operating it by machine power. 95

Let it be assumed that by a suitable spout, the succotash or mixed grain to be separated, are delivered into the upper end of the rotary sieve. Under the rotation of the sieve, the corrugations thereof, act as flights 100 which continuously pick up the grain, carry the same toward the top of the sieve, and precipitate the same back onto lower corrugations of the sieve. Under this action, the grain is continuously worked toward the 105 lower end of the sieve; but under the repeated elevations and precipitations thereof,

the oats will be dropped endwise onto the corrugations of the sieves and will pass through the same, while the wheat will be worked on and delivered out of the lower end of the sieve. In fact, the oats when dropped and when in anywise moved in the corrugations of the sieve, find opposite the same, meshes of the sieve through which they can pass endwise, so that the chances 10 of the oats working through the sieve are many times greater than in a truly cylindrical sieve. In fact, in the truly cylindrical or smooth sieve, the oats which naturally lie flat, can roll or slide flatwise on the sieve surface and have a chance to get through the meshes thereof, only when upended by some action, such as dropping onto the sieve surface. With the corrugated sieve surface, the grain cannot roll back 15 from one corrugation to another until it has been carried near to the top of the sieve, but all of the shifting movements thereof, within the corrugations, give the oats a chance to go endwise through the meshes of the sieve. The corrugations of the sieve very 20 greatly strengthen the same so that it is not only made self-sustaining in form, but also rigid and capable of carrying a considerable load of grain therein. Furthermore, it may be very cheaply made. In actual practice, I have found that by the use of this corrugated rotary sieve, not only ordinary oats 25 and pin oats, but also wild oats may be readily separated from wheat. Moreover, the separating action of this corrugated metal sieve is so efficient that with the proper mesh in the sieve, wild oats may be separated even from tame oats. From this state-

ment, it also, of course, follows, that wild oats may be readily separated from barley, 40 rye, and the like. In fact, by this improved sieve, almost any kind of relatively slim and long objects may be separated from relatively short and thick objects. The efficiency of the separation, as has been made 45 clear, is due to the efficient manner in which the relatively long and slim objects are presented endwise to the sieve surface.

What I claim is:

1. The combination with a rotary sieve 50 made from stiff self-sustaining woven wire netting bent to form longitudinally extended circumferentially spaced corrugations, of a shaft extended axially through said sieve and provided with sieve-supporting heads 55 including radial arms and connecting hoops, the hoops being co-axial with said sieve and engaging with the corrugations thereof only at the portions of the corrugations immediate adjacent the hoops. 60

2. A tubular rotary sieve made from stiff self-sustaining woven wire netting bent to form longitudinally extended circumferentially spaced corrugations, the bottoms of 65 the corrugations being rounded and said corrugations serving as flights to elevate and precipitate the material to be separated and through the lateral walls of which some of the material is permitted to move in an endwise direction under rotation of the sieve. 70

In testimony whereof I affix my signature in presence of two witnesses.

OLE L. LARSON,
